SMOKING PIPE

Louis Benjamin, Max Benjamin, and Benjamin Benjamin, Brooklyn, N. Y.

Application August 13, 1940, Serial No. 352,432

1 Claim. (Cl. 131—206)

Our invention relates to improvements in tobacco smoking pipes, and the primary object of the present invention is to provide a smoking pipe embodying cooperating features of construction in such an arrangement that the smoke is cooled and rid of noxious substances before it reaches the mouth of the smoker, and whereby the charge of tobacco burns more evenly and requires less relighting.

Other important object and advantages of our invention will be apparent from a reading of the following description taken in connection with the drawing, wherein for purposes of illustration we have shown a preferred embodiment of our invention.

In the drawing—

Figure 1 is a general side elevational view illustrating embodiment of the present invention in a conventional appearing smoking pipe.

Figure 2 is a bottom plan view of Figure 1.

Figure 3 is a fragmentary enlarged longitudinal sectional view taken substantially on a line 3—3 of Figure 2, and disclosing the interior arrangements.

Referring in detail to the drawing, the numeral 5 generally designates the smoking pipe as a whole which consists of a bit 6 having a reduced terminal portion 7 snugly fitting in a conforming socket 8 formed in the free end of the tubular stem 9 which projects from the bowl 10. The bowl 10 has a conventional form of tobacco burning chamber 11 which differs from the conventional arrangement by being located at a greater than ordinary height above the stem 9 so that the bottom 12 of the chamber is spaced above the upper wall of the longitudinal substantially cylindrical passage 13 which extends from the inner end of the socket 8 to a point beyond the vertical center of the tobacco chamber, as indicated by the numeral 14. The tobacco chamber 12 has an axial vertical opening 15 which is axially aligned with a larger threaded opening 16 formed in the bottom wall of the stem 9. Threaded in the opening 16 is a plug 17 of suitable metal or non-metallic material and this plug is provided with a frustro-conical countersink 18 to receive the frustro-conical head 19 on the screw 20, the upper part of the frustro-conical opening being threaded to threadably accept the threaded shank portion of the screw so that when the screw is in place with the head thereof in the frustro-conical recess 18 the upper part of the shank extends into the opening 15 in the tobacco bowl chamber and is in concentrically spaced relation to the sides of the opening 15.

The screw 20 is provided with a vertical longitudinal passage 22 which opens through its upper end, which is normally substantially flush with the bottom of the tobacco chamber 12 and the lower end of this passage 22 opens into a transverse passage 23 which is formed in the shank of the screw and opens through both sides thereof at a point about midway the upper and lower walls of the passage 13 in the stem 9, all as clearly shown in Figure 3 of the drawing.

The bit 6 has inserted in the bore thereof for a considerable distance as indicated by the numeral 24 the relatively small diameter tube 25 which is of suitable metal or non-metallic material and extends in concentrically spaced relation to the walls of the passage 13 and has the left hand end thereof beveled as indicated by the numeral 26 and located in spaced relation to the adjacent side of the screw 20, whereby with a charge of tobacco lit in the chamber 11 in the bowl of the pipe, drawing by the smoker upon the bit 6 will produce a suction through the tube 25 which is communicated to the passage 13 and through the hole 15 in the bottom of the bowl and through the passages 23 and 22, to the bottom of the charge of tobacco, with the result that smoke is drawn down through the charge of tobacco and passes through the opening 15 and through the passages 22 and 23 through and around and in intimate contact with the screw 20 and its threads, so that noxious material entrained in the tobacco smoke and vapors will be separated out of the tobacco smoke and fall and accumulate in the passage 13, whence the same may be easily removed upon removal of the screw and the plug 17, without the use of any special tool. With the noxious elements separated and contained in the passage 13, the smoke will pass around the small tube 25 and in its transit in contact with the tube 25 and in the relatively large air space provided by the passage 13 be cooled and upon entering the beveled end of the tube 25, be further cooled in its transit through the tube 25 and into the bore 27 of the bit 6, where the tobacco smoke arrives in a cool and sweet condition unimpaired by saliva, and products of combustion.

Due to the unique arrangement of the screw and its cooperative arrangement relative to the opening 15 in the bottom of the tobacco bowl, a natural draft appears to be brought about which maintains and improves the combustion of the tobacco in the tobacco chamber 11, so that the tobacco does not go out as it ordinarily does in a smoking pipe several times during the

consumption of a single charge, but continues to burn until the bottom of the bowl is reached. The arrangement of the screw in the opening 15 acts in much the same manner as the grate in a coal stove or the like, wherein the fuel charge is suspended in such a manner that air is circulated therein to assist and continue the combustion. Thus it will be understood that the present arrangement makes available for the tobacco charge a larger than ordinary amount of oxygen for purposes of complete and uniform combustion. As a result of this theory of combustion fewer noxious products of combustion are created and those which are unavoidably produced are in a less objectionable condition. 15 A corollary to this is that there is a smaller accumulation within the air cooling passage 13 of noxious substances, with the final result that there is less cooling work to be done and less separation of tobacco smoke required to bring to the mouth of the smoker a dry, cooled, and clean tobacco smoke.

Although we have shown and described herein a preferred embodiment of our invention, it is to be definitely understood that we do not desire to limit the application of our invention thereto, except as may be required by the scope of the subjoined claim.

Having described the invention, what is claimed as new is:

A smoking pipe consisting of a bowl having a stem, said bowl having a tobacco chamber having its bottom on a level above said stem, said stem being formed with a relatively large diameter bore acting as an air cooling passage, 35

said passage extending from a point adjacent the rear end of said stem to a point adjacent the far side of and below said tobacco chamber, a bit inserted into the rear end of said air cooling passage, said bit having a bore, a cooling tube inserted in the bore of the bit and extending through said air cooling passage in spaced relation to the sides thereof, said air cooling passage being formed with a clean-out opening in its bottom wall beneath said tobacco chamber and said tobacco chamber being formed with a substantially centralized smoke opening substantially axially aligned with said clean-out opening, said cooling tube having its front end terminating rearwardly of the smoke opening, and a plug fitting said clean-out opening, said plug having a reduced shank rising therefrom and extending into said smoke opening in spaced relation to its sides, said shank having an axial bore opening through its upper end, said shank further having a transverse bore located in said air cooling passage and having communication with the lower end of said axial bore, said transverse bore being in axial alignment with the tube and disposed adjacent the front end of the tube, said plug comprising a disk threaded into said clean-out opening, said disk being formed with a vertical threaded bore and said reduced shank having external threads engaged with said threaded bore, and means to turn said shank relative to said plug to vertically adjust the shank.

LOUIS BENJAMIN.
BENJAMIN BENJAMIN.
MAX BENJAMIN.
